UNITED STATES PATENT OFFICE.

MICHAEL DE BONIS, OF ABBOTSFORD, BRITISH COLUMBIA, CANADA.

STAPLE.

Application filed August 1, 1924. Serial No. 729,471.

This invention relates to staples such as are used in securing wires or the like to walls, or other supports, the invention having for an object the provision of a novel 5 form of staple provided with a head to facilitate driving thereof.

For further comprehension of the invention, and of the objects and advantages thereof, reference will be had to the following 10 description and accompanying drawing, and to the appended claims in which the various novel features of the invention are more particularly set forth.

Fig. 1 is a side view showing the preferred form of the staple.

Fig. 2 is a transverse sectional view thereof.

As shown in the drawing a strap 18 of suitable shape is arranged to form the legs 20 of the staple and has the pointed ends 19. This strap presents intermediate its ends a flat portion 18' which extends at right angles to the legs, while immediately adjacent the ends of this flat portion the staple 25 is doubled inward upon itself as at 20 to form a support for a head element in the form of a sheet member 21 which extends between the parts 18' and 20 and which has the ends thereof doubled back upon itself

as at 21' to engage the sides of the part 18' 30 and thereby hold itself in position.

It will be understood that the staple is formed from a metal strap and has pointed ends 19. The said strap is bent so that its ends 19 are at right angles thereto, the head 35 element in the form of a sheet member 21 is placed into the part 18' and its ends are doubled back upon itself as at 21' so as to engage the sides of the part 18'; the said strap is then doubled inward upon itself 40 as at 20.

Having thus described my invention what I claim as new and desire to protect by Letters Patent of the United States is as follows:—

In a staple having a central portion and a sheet metal head engaged under said central portion and having the ends thereof turned backwardly to engage the sides of said central portion, said staple having legs 50 depending from said central portion, the combination of projections depending from said legs, and engaging beneath said head to hold said head in place.

In testimony whereof I have affixed my 55 signature.

MICHAEL DE BONIS.
